GUN BARREL SEALING DEVICE

John M. Huckabee, Shreveport, La.

Application November 3, 1953, Serial No. 389,964

3 Claims. (Cl. 42—1)

This invention relates to a novel and improved device for sealing the barrels of rifles, shotguns and revolvers and for cleaning such barrels, the primary object of the invention being to provide a more practical, efficient and reliable device of this kind which is of simpler and more rugged construction.

Another important object of the invention is to provide a gun barrel sealing device which cannot be removed with ordinary pliers, wrenches, or screw drivers, so that the device more securely and safely protects a gun barrel from being loaded by unauthorized persons, such as children, and from the entrance therein of foreign matter.

A further important object of the invention is to provide a device of the character indicated above which is readily convertible for cleaning gun barrels, and which is readily convertible to fit barrels of different gauges.

Other important objects and advantageous features of the invention will be apparent from the following description and the accompanying drawings, wherein, for purposes of illustration rather than limitation, specific embodiments of the invention are set forth in detail.

In the drawings:

Figure 1 is a side elevation of a single barrel shotgun, with the barrel in longitudinal cross section and containing a device in accordance with the present invention in sealing relation thereto;

Figure 2 is a fragmentary view similar to Figure 1, showing the barrel broken and the said device partly in section;

Figure 3 is an enlarged side elevation of said device alone with portions thereof in longitudinal section;

Figure 4 is an enlarged fragmentary perspective view of the cap;

Figure 5 is a perspective view of the special wrench for the cap;

Figure 6 is an enlarged, contracted longitudinal section taken through a gun barrel and through parts of another embodiment of the present invention in sealing relation to the gun barrel;

Figure 7 is a contracted view similar to Figure 3, the plug of the device being replaced by a cleaning brush;

Figure 8 is a fragmentary longitudinal section showing said brush in use;

Figure 9 is a view similar to Figure 7 showing the brush replaced by a swab holder and swab; and

Figure 10 is a transverse section taken on the line 10—10 of Figure 9.

Referring in detail to the drawings, wherein like numerals designate like parts throughout the several views, and first to Figures 1 to 5 thereof, the numeral 11 generally designates a shotgun having a barrel 12 having a forward end 13 and a rearward breech or chamber end 14.

A device in accordance with the present invention and generally designated 15 comprises a plug 16 for engagement in the chamber end 14 of the barrel 12, and a rod 17, and a cap 18. The plug 16 is a cylindrical body which has a close fit in the barrel 12 and has on

2

its rearward end a lateral flange 19 which seats in the groove 20 of the chamber end 14 of the barrel 12, whereby forward movement of the plug 16 in the barrel 12 is precluded. The plug 16 has a threaded axial socket 21 opening through its forward end 22.

The rod 17 is of relatively small diameter and has a threaded rearward end portion 23 arranged to thread into the plug socket 21.

Non-rotatably fixed upon the forward end portion of the rod 17 is the cap 18 which comprises a cylindrical body 24 fitting the forward end 13 of the barrel 12 and a lateral flange 25 on the forward end of the body 24. The flange 25 is of substantially the same outside diameter as the barrel 12, and is bevelled, as indicated at 26, so as to fair into the barrel end 13, and so as to leave insufficient surface to give purchase to wrench or pliers used in an unauthorized attempt to rotate the cap 18.

The forward end 27 of the cap 18 is provided with a pair of relatively greatly diametrically spaced holes 28, 28 for reception of pins 29, 29 on a special spanner wrench 30 which has a handle portion 31 provided with a hole 32 for engaging the wrench 30 on a key-ring or the like.

The above described device is installed in sealing relation to the barrel 12 by inserting the plug 16 forwardly in the chamber end 14 of the barrel 12, inserting the rod 17 rearwardly into the forward end 13 of the barrel 12 accompanied by the cap 18, in such a way as to engage the threaded rearward end portion 23 of the rod 17 into the threaded socket 21 of the plug 16. Thereupon the special wrench 30 is employed to rotate the cap 18 and the rod 17 until the plug 16 and the cap 18 have their flanges 19 and 25, respectively, tightly engaged with the rearward and forward ends, respectively, of the barrel 12. The barrel 12 cannot then be loaded and its interior is sealed against the entrance of any foreign matter. Because of the special arrangement of the forward end 27 of the cap 18 and its bevelled flange 25, the cap cannot be effectively loosened by the use of any usually available tools, but the special wrench 30 is required to be used.

Referring now to Figure 6 of the drawings, there is therein shown another embodiment of the invention, which is generally designated 15a. In this embodiment the plug 16a has telescoped thereon one or more shim sleeves 33, 34 having forward end walls 35, 36 provided with central holes 37, 38 freely passing the threaded portion 23' of the rod 17a into the plug socket 21a. The plug 16a has on its rear end a flange 19a which engages a flange 39 on the rear end of the inner sleeve 33, and the flange 39 of the inner sleeve 33 engages a flange 40 on the rear end of the outer sleeve 34, with the flange 40 engaging the barrel chamber groove 20. Through the provision and described arrangement of the shim sleeves 33 and 34 the device 15a can be adapted to barrels of three different gauges.

The cap 18a of the device 15a has telescoped thereon inner and outer shim sleeves 41 and 42, respectively, which have lateral flanges 43 and 44, respectively, on their forward ends. The cap flange 25a engages the inner sleeve flange 43, and the inner sleeve flange 43 engages the outer sleeve flange 44, whereby the cap 18a is adaptable to barrels of three different gauges.

Referring now to Figures 7 and 8 of the drawings, a brush head 45 is shown which can be substituted for the plugs 16 and 16a on the threaded rod end portions 23 or 23a of the above described embodiments, so that the devices can be used for brush cleaning the bore of the barrel 12.

Figures 9 and 10 show a swab head 46 which can replace the plugs 16 or 16a on the rod ends 23 or 23a of the above described embodiments. The swab head 46 has therein a longitudinal transverse slot 47 through

which a swab 48 can be engaged for swab cleaning of the bore of the barrel 12.

The brush head 45 and the swab head 46 have threaded bores 49 and 50, respectively, which receive the threaded rod end portions 23 and 23a.

What is claimed is:

1. In a gun barrel sealing device, a plug insertible into the rearward chamber end of a barrel having a flange engageable with the rearward end of the barrel and provided with a threaded socket opening through the forward end of the plug, a rod having a threaded rearward end portion threaded into said socket, a cap fixed on the forward end of said rod including a body fitting into the bore of the barrel at the forward end of the barrel, said body having a lateral flange engageable with the forward end of the barrel, and means for rotating said cap to thread the rod end portion into said socket and to unthread the rod end portion out of said socket, and inner shim sleeves telescoped on said plug and on said cap body having lateral flanges engaged by the flanges of the plug and cap, and outer shim sleeves telescoped on the inner shim sleeves and having lateral flanges engaged by the lateral flanges of the inner shim sleeves.

2. In combination, a gun barrel having a bore, a breech end and a muzzle end, a cap comprising a body smaller in diameter than said bore and having an outer end, a lateral flange on said outer end larger in diameter than said bore, said cap further comprising a removable inner sleeve engaged on said cap body, a removable outer sleeve engaged on said inner sleeve, said sleeve having outer ends, lateral flanges on the outer ends of the sleeves, the flange of the outer sleeve being engaged with the muzzle end of the barrel, the flange of the inner sleeve being engaged with the flange of the outer sleeve, and the flange of the cap body being engaged with the flange of the inner sleeve, a rod smaller in diameter than said bore and extending within said bore, said rod having an outer end fixed to the cap body and a threaded inner end, and a plug element threaded on the inner end of the rod and engaged in the breech end of the barrel.

3. In combination, a gun barrel having a bore, a breech end and a muzzle end, a cap comprising a body smaller in diameter than said bore and having an outer end, a lateral flange on said outer end larger in diameter than said bore, said cap further comprising a removable inner sleeve engaged on said cap body, a removable outer sleeve engaged on said inner sleeve, said sleeve having outer ends, lateral flanges on the outer ends of the sleeves, the flange of the outer sleeve being engaged with the muzzle end of the barrel, the flange of the inner sleeve being engaged with the flange of the outer sleeve, and the flange of the cap body being engaged with the flange of the inner sleeve, a rod smaller in diameter than said bore and extending within said bore, said rod having an outer end fixed to the cap body and a threaded inner end, and a plug element threaded on the inner end of the rod and engaged in the breech end of the barrel, said plug element comprising a plug smaller in diameter than the gun barrel having a threaded socket receiving the threaded end of the rod, said plug having an outer end, a lateral flange on the outer end of the plug bearing against the breech end of the barrel, a removable inner sleeve on said plug having an outer end having a lateral flange thereon bearing against the plug flange, and a removable outer sleeve on said inner sleeve having an outer end having a lateral flange thereon bearing against the flange of the inner sleeve.
